UNITED STATES PATENT OFFICE.

HEINRICH SCHICKLER, OF WILMERSDORF, NEAR BERLIN, GERMANY.

COLORING-TOOL.

SPECIFICATION forming part of Letters Patent No. 691,184, dated January 14, 1902.

Application filed August 17, 1901. Serial No. 72,429. (No model.)

To all whom it may concern:

Be it known that I, HEINRICH SCHICKLER, master painter, a subject of the King of Würtemberg, residing at No. 7 Ringbahnstrasse, 5 in Deutsch Wilmersdorf, near Berlin, in the Empire of Germany, have invented certain new and useful Improvements in Coloring-Tools, of which the following is a specification.

- 10 The invention relates to an apparatus for use in the decoration of dwelling-rooms and the like, and has for its object to permit of decoration-lines of various colors and widths, as required in the painting of borders, as well 15 as endless friezes and ornamentations upon such walls and ceilings to be effected or produced by a simple movement of the apparatus in a longitudinal direction.

In the accompanying drawings a construction for carrying my invention into effect is shown, in which—

Figure 1 is a side elevation; Fig. 2, a plan partly in longitudinal section.

Upon a rigid axis *a*, carried by the shanks 25 *b* of a movable frame-carrier, a number of rotatable disks or rollers *c* are mounted, corresponding in number, width, and distance from each other to the decorative bordering or ornamentation to be produced. The spacing 30 or location of the disks to each other can, as shown in the drawings, be adjusted by movable rings or collars of varying width within certain limits to any desired degree. The circumference of each of the disks *c* is provided with a plain or pattern-producing covering *d*, of felt or other suitable color-absorbing material, and beneath each disk a trough *f* is arranged, each of these troughs being carried by the middle shank *g* of the said frame- 35 carrier in such a manner that a portion of the circumference of each disk is caused to dip into the liquid or pasty coloring material contained in the trough belonging or attached beneath the same.

40 The improved apparatus is guided along the edge of the ceiling or wall in such manner that each of the above-mentioned disks or

rollers uniformly touch the surface to be decorated, whereby, as is apparent, a number of borders, friezes, and ornamentations will be 50 produced in form, breadth, and color corresponding to the type of the respective rollers and the color of the material in the said trough. The handle *h* insures a reliable guiding of the apparatus along the ceiling or the wall. 55

To conveniently insure the true or straight movement of the apparatus, as well as to prevent a tipping of the same when traveling along the respective wall or ceiling, the apparatus is provided with two horizontal and two 60 vertical guide-rollers *k* and *l*, mounted upon an arm *i*, this arm forming a continuation, so to speak, of the axis *a* and projecting beyond the shanks *b* of the frame-carrier. It will thus be apparent that these guide-rollers when 65 brought to bear against and travel along a suitably-held rule or against a straight edge of the wall or ceiling will cause the desired accuracy in the movement of the apparatus to be perfectly attained. 70

What I claim, and desire to protect by Letters Patent, is—

In an improved apparatus for the production of variously-colored plain or ornamental borders or friezes upon ceilings and walls the 75 combination with a number of disks or rollers *c* provided at their circumference with a plain or pattern-producing covering of felt or other suitable paint-absorbing material, the said disks being mounted upon a common 80 axis *a* and optionally adjustable in their distance apart by intermediate rings or collars *e*, of coloring-troughs *f*, interchangeably arranged under each disk and carried by the middle shank *g* of a frame-carrier and lastly 85 of guide-rollers *k* and *l*, mounted upon a projected arm of the said axis, all operating substantially and for the purpose as described.

In witness whereof I have hereunto set my hand in presence of two witnesses.

HEINRICH SCHICKLER.
